STRIP EMBOSsing IMPLIMENT

Benedict E. Bogaus, Los Angeles, Calif.
(333 N. Foothill Road, Beverly Hills, Calif.)

Filed Jan. 31, 1963, Ser. No. 73,385

Term of patent 3½ years

(Cl. D64—11)

FIG. 1.

FIG. 2.

FIG. 3.

*FIG. 4.**FIG. 5.**FIG. 6.*FIGURE 1 is a perspective view of a strip embossing implement showing my new design in accordance with the present invention;

FIGURE 2 is a top plan view thereof;

FIGURE 3 is a right side elevational view;

FIGURE 4 is a left side elevational view;

FIGURE 5 is a bottom plan view;

FIGURE 6 is a front elevational view; and

FIGURE 7 is a rear elevational view thereof.

The essential features of my design reside in the portions shown in solid lines.

I claim:

The ornamental design for a strip embossing implement, substantially as shown and described.
